VAPOR-ELECTRIC DEVICES

Alfred H. Laidig, Essex County, N. J., assignor to Westinghouse Electric Corporation, East Pittsburgh, Pa., a corporation of Pennsylvania

Application May 28, 1952, Serial No. 290,587

7 Claims. (Cl. 313—328)

This invention relates to vapor-electric devices such as are generally known as ignitrons.

There are in the art several examples of ignitrons utilizing semi-solid or sponge cathodes, and the present invention contemplates improvement thereover.

Approached in its broader aspects, an objective of the present invention is to obtain a more stable and unfailing arc discharge in an ignitron.

A further object of the invention is to provide for a more effective cycle of vaporization of the liquid cathode material at the region of arc instigation.

More specifically, the invention provides for a copious supply of the liquid cathode material at that region of the sponge cathode body at the point of arc instigation by the ignitor.

Another object of the invention is to provide for the rapid absorption of condensed cathode material and provision of a reservoir for reception thereof, in combination with means for returning the liquid cathode material to the region of arc instigation.

Other objects of the invention will appear to persons skilled in the art to which it appertains as the description proceeds, both by direct reference thereto and by implication from the context.

Referring to the accompanying drawing in which like numerals of reference indicate similar parts throughout the several views;

Figure 1 is a vertical section of an essential portion of an ignitron wherein the present invention is included in one form thereof;

Figure 2 is a cross-section on line II—II of Fig. 1; and

Figure 3 is a vertical section similar to Fig. 1 and showing a modified form of cathode body and of the invention adapted thereto.

In the specific embodiment of the invention and associated ignitron construction illustrated in the drawing, but without limiting to details thereof, a sealed cylindrical casing 10 of steel or other sturdy material is shown having a bottom 12 integral therewith and having, at a distance above said bottom, an anode 13 appropriately supported and insulated from the casing as usual in the art. Between said anode 13 and bottom 12 is an ignitor 14 here shown located axially of the container and directed toward and terminating at its bottom in engagement with a sponge cathode body 15 located substantially on the bottom wall 12. Said ignitor may be composed of materials, such as boron, boron carbide and boron nitride as used for ignitors of the prior art, or may be of such other material or materials adapting it more especially to the present invention.

Said sponge cathode body 15 preferably fits the container at its periphery and may be suitably held in place, as by means of a plurality of indentations 16 made in the wall of the container, as shown in Figures 1 and 2 such that the indentations project into the periphery of the cathode body. Alternatively, retention of the cathode body 15a, as shown in Fig. 3, may be accomplished by a stud 16a projecting from the bottom wall 12a into the

2

container and having screw-thread engagement with said body.

In any event, the cathode body is constructed to provide a hollow 17 at its under side to constitute a reservoir for the reconstructing cathode liquid, which usually is mercury 18. The construction of the cathode body is preferably such that it not only fits against the side wall of the container at its periphery, but also provides a bottom rim 19 next the periphery to rest upon the said bottom wall of the container and thereby form and maintain the hollow 17 at the underside of said body with the bottom of the container utilized as the bottom of the reservoir.

It is furthermore desirable to bevel the upper peripheral corner of the cathode body, and thereby provide a peripheral trough 20 next the side wall of the container, between it and the surface of the cathode body to receive condensed mercury or the like which gravitates down the said side wall. The mercury then passes through the sponge body into reservoir 17. To aid the mercury and obtain faster draining of the trough, a plurality of capillary passages 21 are provided in the cathode body from proximity to the beveled edge surface thereof to the said reservoir. The said passages preferably slope downward toward the reservoir so as to take advantage of gravity in addition to capillarity for aiding in the flow of the mercury.

At the midsection of the cathode body there is shown a downwardly extending boss or hub 22 the under face of which is in proximity to but definitely spaced from the bottom wall 12 of the container. In effect, therefore, this boss or hub is submerged in the mercury or the like contained in the reservoir. This boss or hub is provided with a plurality of capillary passages 23 which are open at the under face of the hub and extend approximately to the surface of the cathode body in proximity to the location of the ignitor. There is, however, a thin closure of the sponge material of the cathode at the upper ends of the capillary passages through which the mercury may seep in use. The proximity of the upper ends of the capillary passages is conducive to a copious flow of mercury to the upper surface of the cathode. The fact that the lower ends of the capillary passages are always submerged in the mercury pool in the reservoir assures a constant supply to the upper surface of the cathode.

It is within the scope of the invention to use any desired fabrication of cathode body. In Fig. 1 the body is shown as in most part of one sponge material and having a central disc or insert 24 at its upper surface for arc striking purposes. By way of example, the major part of the cathode body may be a sponge of sintered iron, whereas the restricted arc striking insert 24 may be of some more refractory sponge material such as sintered ruthenium, molybdenum or the like. With a compound body of this character, the capillary passages may extend upward to the under portion of the insert and thus feed mercury directly thereto and in addition to the mercury which is fed through the pores or interstices of the sponge.

Where, as shown in Fig. 3, a cathode body of one sponge material is employed, that is, without an insert, the capillary passages 23 preferably stop short of the upper surface so the mercury has to feed through a closure layer of the sponge material. This not only gives desired distribution of the mercury on the surface, as well as a restriction in droplet size, but avoids spurts of mercury which might occur if the passages were open at their upper ends. The sponge body may be sintered iron alone or in combination with some other material mixed therewith, such as a mixture of iron and molybdenum, or may be sintered molybdenum or other material or combination of materials.

I claim:

1. A sponge cathode comprising a body portion of a sponge material having a reservoir next one face thereof, and having capillary passages open to said reservoir and extending therefrom in said body portion.

2. A sponge cathode comprising a body portion of sponge material having a reservoir and a trough separated by an intervening thickness of said sponge material, said intervening thickness of the sponge material having capillary passages part way through the same.

3. A sponge cathode comprising a body portion of sponge material having a reservoir and a hub dipping into said reservoir, and said hub having capillary passages extending in a direction from the reservoir to an upper part of the body portion.

4. An ignitron comprising a side wall and a bottom wall, a sponge cathode extending to engagement with both of said walls, said cathode providing a reservoir between a portion thereof and the bottom wall and providing a trough between a portion thereof and the side wall.

5. An ignitron comprising a side wall and a bottom wall, a sponge cathode extending to engagement with both of said walls, said cathode providing a reservoir between a portion thereof and the bottom wall and providing a trough between a portion thereof and the side

wall, and said cathode having capillary passages therein substantially from said trough to said reservoir.

6. An ignitron comprising a side wall and a bottom wall, a sponge cathode extending to engagement with both of said walls, said cathode providing a reservoir between a portion thereof and the bottom wall and providing a trough between a portion thereof and the side wall, and said cathode having a hub depending into said reservoir.

10. 7. An ignitron comprising a side wall and a bottom wall, a sponge cathode extending to engagement with both of said walls, said cathode providing a reservoir between a portion thereof and the bottom wall and providing a trough between a portion thereof and the side wall, said cathode having a hub depending into said reservoir, and said cathode having capillary passages opening into said reservoir with some of said passages in said hub and others extending substantially to said trough.
